DESIGN FOR A TRANSPARENCY VIEWER

John Warren Gillon, Rochester, N. Y., assignor to
Eastman Kodak Company, Rochester, N. Y., a
corporation of New Jersey

Application October 25, 1939, Serial No. 87,845

Term of patent 7 years

To all whom it may concern:

Be it known that I, John W. Gillon, a citizen of the United States, residing at Rochester, in the county of Monroe and State of New York, have invented a new, original, and ornamental Design for a Transparency Viewer, of which the following is a specification, reference being had to the accompanying drawing, forming a part thereof.

In the drawing:

Fig. 1 is a perspective view taken from the front

and showing a transparency viewer embodying my new design.

Fig. 2 is a front elevation of the transparency viewer shown in Fig. 1, and

Fig. 3 is a side elevation of the transparency viewer shown in the preceding figures.

I claim:

The ornamental design for a transparency viewer, as shown.

JOHN WARREN GILLON.
